UNITED STATES PATENT OFFICE.

PHILIP V. CONOVER, OF UVALDE, TEXAS.

ELECTRIC CAR-BRAKE.

SPECIFICATION forming part of Letters Patent No. 224,880, dated February 24, 1880.

Application filed December 3, 1879

To all whom it may concern:

Be it known that I, PHILIP VORUS CONOVER, of Uvalde, in the county of Uvalde and State of Texas, have invented a new and Improved Electric Car-Brake, of which the following is a specification.

The object of my invention is to provide a new and improved car-brake, which is actuated by the rotation of the car-wheels and is governed and regulated by electricity.

The invention consists in a car-brake formed of a pinion attached to the car-axle, the pinion taking in a ratchet-wheel provided with a projecting pin, that enters into the slots of a wheel provided with a sleeve, upon which the brake-chain is wound, which sleeve can be moved on the axle by means of a lever that is actuated by a rod passing into a helix connected with a battery on the locomotive. A pawl-tooth that is held in place by a slide prevents the unwinding of the brake-sleeve until the slide is removed by a lever actuated by a rod passing into a helix likewise connected with the battery on the locomotive.

In the accompanying drawings, Figure 1 is a plan view of the under side of the car. Fig. 2 is a vertical longitudinal sectional elevation of the same on the line $x-x$, Fig. 1. Fig. 3 is a vertical cross-sectional elevation on line $y-y$, Fig. 1.

Similar letters of reference indicate corresponding parts.

The pinion A is fastened to the car-axle B, and takes in the ratchet-wheel C, provided with a pin, D, curved beveled projections E E, and mounted on the shaft F, supported in the two bearings G and G', fastened to the under side of the car-floor H. A ratchet-wheel, I, provided with curved slots i i, into which the pin D passes, and a sleeve, J, upon which the brake-chain is wound, is loosely mounted on the shaft F. A lever, K, is loosely attached to the shaft F adjoining the sleeve, and the upper end of the lever is attached to rod L, which passes into a helix, M, fastened to the under side of the car-floor. The lever rests against the shoulder g in the bearing G', and is thus fulcrumed. A slide, N, provided with a vertical flange, O, is suspended from a beveled cross-bar, P. The slide N has a beveled groove in its upper edge, into which the

slide Q fits. Q is fastened to the lever R, fulcrumed at S, and attached to the rod T, passing into the helix U. The slide is also provided with a slot, V, through which a slotted cam-tooth, W, provided with a head, z, passes. The helices are connected with a battery on the locomotive.

The operation is as follows: As the pinion A is attached to the axle B it will revolve with it when the train moves forward in the direction of the arrow a , and A will cause the ratchet-wheel C, in which its teeth take, to rotate in the direction of the arrow c' . When the circuit of the wires connected with the helix M is closed, the end of the lever K is drawn in the direction of d' and the wheel I is pressed against C, the pin D enters one of the curved slots i i in I, and the wheel I, with the sleeve J, rotates with C. As the brake-chain is fastened to the staple j, the chain will be wound up tight on the sleeve J by the rotation of the same, and the brake-shoes will be pressed to other wheels of the car with considerable force. As the wheel C rotates, the beveled projections E E gradually press the vertical flange O in the direction of e' , and this flange presses the wheel I away from C, so that the pin D no longer takes in the slots i i. The pawl-tooth W rests in the teeth of I and prevents the brake-chain from unwinding.

If it is desired to further slacken the speed of the train, the current is again closed, and the above operation repeats itself until the train is stopped, the pawl-tooth W permitting I to turn in the direction of c' , but preventing a movement in the opposite direction. During all this time the head z of the pawl-tooth W was firmly clamped between the top of N and the slide Q.

If it is desired to loosen the brakes, the circuit passing through the wires connected with the helix U is closed, and the rod T will be drawn in the direction of f' , the slide Q will move back from the head of the pawl-tooth W, and the same can give way to the pressure of I, and the brake-chain is unwound. The pawl-tooth W is slotted and held by a pin, p', and operates equally efficiently for all movements of the train.

The levers K and R are connected by the

rod Z, so that when one operates it always sets the other in position for operation.

Having thus described my invention, what I claim as new, and desire to secure by Letters Patent, is—

1. In a car-brake, the combination of the car-axle B with the pinion A, the ratchet-wheel C, provided with a pin, D, the wheel I, provided with a sleeve, J, and the lever K, actuated by a rod, L, passing into a helix, M, substantially as herein shown and described, and for the purpose set forth.

2. The combination of the wheel C, provided with slanting projections E E and pin D, with

the wheel I, having slots *i i*, and with the flange O and the pawl-tooth W, substantially as herein shown and described, and for the purpose set forth.

3. The combination of the pawl-tooth W with the slides N and Q, the lever R, the rod T, and the helix M, substantially as herein shown and described, and for the purpose set forth.

PHILIP VORUS CONOVER.
